CLAIM

The ornamental design for a court lamp as shown and described.

DESCRIPTION

FIG. 1 is a front, right, top perspective view of a court lamp showing our new design;

FIG. 2 is a back, left, bottom perspective view thereof;

FIG. 3 is a front view thereof;

FIG. 4 is a left view thereof;

FIG. 5 is a right view thereof;

FIG. 6 is a back view thereof;

FIG. 7 is a top view thereof;

FIG. 8 is a bottom view thereof;

FIG. 9 is an enlarged view of the encircled area 9 of FIG. 1;

FIG. 10 is an enlarged view of the encircled area 10 of FIG. 1;

FIG. 11 is an enlarged view of the encircled area 11 of FIG. 2;

FIG. 12 is an enlarged view of the encircled area 12 of FIG. 3;

FIG. 13 is an enlarged view of the encircled area 13 of FIG. 5; and,

FIG. 14 is an enlarged view of the encircled area 14 of FIG. 7.

The broken lines shown on the drawings depict portions of the court lamp that form no part of the claimed design. The dash-dot-dash broken lines show the boundaries of the enlarged views and form no part of the claim thereof.

1 Claim, 14 Drawing Sheets
